LATCHING AND DOOR HINGING MEANS AND ARRANGEMENT THEREOF IN A CABINET STRUCTURE

Frank G. Steiner, Miami Beach, Fla., assignor to Steiner Sales Company, Salt Lake City, Utah, a corporation of Utah

Original application May 24, 1940, Serial No. 336,954. Divided and this application August 4, 1942, Serial No. 453,551

4 Claims. (Cl. 292—189)

This application is divisional of my copending application Serial No. 336,954, filed May 24, 1940, and is particularly concerned with a two-door cabinet structure and hinging and latching mechanisms for the door thereof.

An object is to provide a positive lock which automatically locks when the door is closed, and in which the lock is particularly adapted for doors for medicine cabinets which have mirrors mounted thereon and in which the mirror has an area substantially equal to that of the door. An object is to provide a construction which does not require drilling through the mirror in order to attach the keeper.

Objects, features and advantages of the invention will appear in the description of the drawings forming a part of this specification, and in said drawings:

Figure 1 is a front view of the closed cabinet;

Figure 2 is a vertical section of the cabinet taken on line 2—2 of Figure 1;

Figure 3 is a horizontal section taken on line 3—3 of Figure 1;

Figure 4 is a horizontal section on line 4—4 of Figure 1, looking upwardly;

Figure 5 is a vertical section on line 5—5 of Figure 1; and

Figure 6 is a detail elevation of the front of the cabinet body, with part of the stiffening and latch-backing flange broken away.

In the drawings, the numeral 1 generally indicates the cabinet, the numeral 2 the upper door, the numeral 3 the lower door, and the numeral 4 the delivery or discharge opening which is formed by the upper edge of the lower door and the lower edge of the upper door, after the doors are closed. The doors are overlapped in such manner that the upper door can hold the lower door closed. See Figure 2.

The upper door is hinged (see Figures 1 and 3) at one side by hinges 5 having vertical pivots 6. The lower door 3 (see Figure 2) swings downwardly about horizontal pivots 7 which pass through U-shaped hinging brackets 8 fixed to the door 3, the arrangement being such that the door can be swung to a position to form a shelf.

A feature of the invention (see Figure 3) is the formation of the sides 10 and the back 11 of the cabinet in one piece of light weight metal, and the utilization of reinforcing flanges 12, also of one piece with the metal sides, not only for stiffening the structure, but for performing other functions to be described, including that of providing an opening for the keeper of the door.

The top of the cabinet (see Figure 2) is formed

of a plate 18 having flanges 19 on four sides which are disposed inside of the back and side-forming elements of a single piece before mentioned. The flanges lie flatly against the inner surfaces of the corresponding sides and back and are suitably attached as by welding. The front flange 19 is secured to flanges 12. The front of the plate 18 is rounded as at 21 by turning part of its flange backwardly against its under surface.

Figure 3 shows the hinging feature, wherein one leaf of the hinge 5 is secured to the inner face of the door and the other leaf 30 is passed through a slot 31 in side 10 and is attached to the inner surface of flange 12.

The upper door 2 is formed of a single sheet of metal turned upon itself on two vertical sides and at the bottom to form a continuous marginal U-shaped groove 51 on three sides and at the front for receiving and retaining the mirror 52. The mirror is introduced from the top. After placement a top U-shaped strip 53 is placed as shown in Figure 2 and secured by screws 54 entering openings in the back of the single piece door.

An important feature is the structure by which the door is latched in closed position. The door is provided on its inner surface with a keeper 56 having a vertical notch or recess 57 at its top. This keeper is L-shaped and is attached by a flat portion to the inner surface of the door. The flange 12 on that side of the cabinet opposite the hinging side is provided with a slot 60 through which the keeper passes. An L-shaped plate 61 acts as a latching element and its lower edge cooperates with the notch 57 of the keeper to secure the door. The plate 61 engages the inner face of the flange and is slidably held by a screw 63 passing through a slot 64 in the side of the cabinet. A latch-operating button 65 is secured to the screw and lies (see Figures 1 and 3) behind the laterally projecting part of the door. The door is so made as to project beyond the outer surface of the cabinet at the top and at the sides and this projection at the sides makes the operating button and the hinges invisible to a person standing directly in front of the mirror or closed door of the cabinet. It is noted that the flange 12 receives the keeper and forms a backing or abutment for the latch.

It is to be noted particularly that the outside appearance of the cabinet is very neat, that there are very few projections, that the plane surfaces are very easy to finish with enamel or paint. The back and sides are formed by bending a

single sheet of metal and the top has flanges welded or otherwise permanently secured within the cabinet.

Another feature is having a single button arranged at a point adjacent the laterally projecting rear face of the door so that for operating the latch the user merely places his finger behind this projecting portion and, using the rear face of the projecting portion as a guide, moves his finger into operative engagement with the button.

Another advantage of the latching mechanism is that an angle-iron is used for the latching member, and the two faces of this iron respectively engage the side wall of the cabinet and a stiffener flange which extends inwardly from the front of the side wall. In this way the latch is not only strengthened but is guided in a corner formed by two wall surfaces, one a flange against which the door closes. The button and the screw which attaches the button are the sole means by which the latch is translatably attached. Thus, a very simple, easily assembled device is provided. The latch is very freely movable because sufficient play is allowed. The latch is strong, due to its angle-iron structure and to the manner of guiding it by two flat surfaces, in this instance arranged substantially at right angles to one another. This corner location between the side wall and the flange is an important feature of this invention from the standpoint of ruggedness, positiveness of operation, and simplicity of construction.

Attention is particularly called to the fact that the front flanges are coplanar and that the rear face of the door when closed is coplanar with the outer surfaces of these flanges. It is to be noted that this novel arrangement of positively flush closure of the door is obtained by the novel structures of the flanges, hinges and keeper and flange recesses. Those leaves of the hinges which are secured to the door are received in depressions of the flanges, which depressions extend inwardly from their front faces, and the keeper of the door is received in the same kind of a depression, which also extends inwardly from the front face of the flange.

I therefore believe myself the first to make a door for a cabinet, particularly one which carries a looking glass, and to so arranged the hinges and the latch in an all metal cabinet that the rear face of the sheet metal door can lie flush with the front face of the cabinet, and so that the door hides the hinges and the operating element for the latch.

What I claim is:

1. A latch for a cabinet which has a side wall having a flange, which flange has an opening through which a keeper of a door for the cabinet

is adapted to pass, said latch comprising a latch members slidably guided by the corresponding inner faces of the wall and flange and adapted to lockingly engage the keeper after passage of the keeper through the opening in the flange, said cabinet having a slot in the side wall, a button at the outer side of the wall and means passing loosely through said wall slot and securing the latch member to said button, said button and securing means retaining said latch member in slidably mounted relation on said cabinet side wall.

2. A gravity-operable latch for a cabinet which has a side wall having an inwardly turned flange at the front, which flange has an opening through which a keeper of a door for the cabinet is adapted to pass, said latch comprising an angle iron having its outer faces slidably guided by the corresponding inner faces of the wall and flange and adapted to lockingly engage the keeper after it has passed through the opening in the flange, said cabinet having a slot in the side wall, a button at the outer side of the wall and a pin passing loosely through said wall slot and securing the latch to the button for gravity operation.

3. A gravity-operable latch for a cabinet having a side wall having at its front an inturned vertical flange which is adapted to be engaged by the inner face of a door for the cabinet, and in which the flange has an opening adapted to be traversed by a keeper on the door, said latch comprising an angle iron slidably guided in the inner angle between and by the side wall and the flange, the cabinet having a slot in the side wall, a button at the outer side of the wall, a pin passing through said wall slot and securing the button to the angle iron, and said keeper having a slot on its upper side into which the lower end of the latch enters by gravity movement to latch the door.

4. A gravity-operable latch for a cabinet having a side wall having at its front an inturned vertical flange which is adapted to be engaged by the inner face of a door for the cabinet, and in which the flange has an opening adapted to be traversed by a keeper on the door, said latch comprising a piece of angle iron slidably guided in the inner angle between and by the side wall and the flange and with the outer faces of the angle iron engaging the corresponding inner faces of the wall and flange, the cabinet having a slot in the side wall, a button at the outer side of the wall, a pin passing loosely through said wall slot and securing the button to the angle iron, and said keeper having a slot on its upper side into which the lower end of the angle iron enters by gravity movement to latch the door closed.

FRANK G. STEINER.
